Primary Examiner — Susan Bennett Hattan*Assistant Examiner* — Jennifer Wright(74) Attorney, Agent, or Firm — Fross Zelnick Lehrman & Zissu, P.C.; Charles T. J. Weigell, Esq.(57) CLAIM

The ornamental design for a dress, as shown and described.

DESCRIPTION

FIG. 1 is a front view of a dress showing my new design; and,

FIG. 2 is a right side view of the dress shown in FIG. 1, with the lower end of the sleeve cut away (with the left side view being a mirror image thereof).

The short dash-long dash broken lines in the drawings define the bounds of the claim and form no part thereof.

The broken line depicting the outline of a person and the sleeves shows unclaimed subject matter.
